HELICOPTER

Paul M. Schroeder, Jr., Fort Worth, Tex., assignor to
Bell Aircraft Corporation, Wheatfield, N. Y.

Application December 2, 1955, Serial No. 39,130

Term of patent 14 years

(Cl. D71—1)

Fig. 1 is a side elevational view of a helicopter showing my new design;

Fig. 2 is a top plan view thereof;

Fig. 3 is a front elevational view thereof; and

Figs. 4, 5 and 6 are sectional outline views thereof taken about on lines IV—V—VI, respectively, of Fig. 1.

The side of the helicopter not shown in the drawings is identical in appearance with that illustrated in Fig. 1.

The essential features of my design reside in those shown in full lines.

I claim:

The ornamental design for a helicopter, as shown and described.
